CLAIM

The ornamental design for a bottle cap, as shown and described.

DESCRIPTION

FIG. 1 is a front, right side, top perspective view of a bottle cap showing my new design;

FIG. 2 is a front, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof, showing the cover portion of the bottle cap in an open position of use.

(Continued)

The broken lines depict portions of the bottle cap that form no part of the claimed design.

1 Claim, 9 Drawing Sheets
